UNITED STATES PATENT OFFICE.

GEORGE W. COY, OF MILFORD, CONNECTICUT, ASSIGNOR, BY MESNE ASSIGNMENTS, TO THE UNITED STATES TELEPHONE MANUFACTURING COMPANY, OF NEW YORK, N. Y.

TELEPHONE-STATION APPARATUS.

SPECIFICATION forming part of Letters Patent No. 253,912, dated February 21, 1882.

Application filed June 25, 1881. (No model.)

To all whom it may concern:

Be it known that I, GEORGE W. COY, a citizen of the United States, residing at Milford, in the county of New Haven and State of Connecticut, have invented certain new and useful Improvements in Telephone-Station Apparatus; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to that class of telephone-station apparatus in which provision is made for preventing communications between two stations from being overheard at other stations on the same main line, this result being accomplished by means of a kind of switch known as a "secrecy-switch," and upon which my invention is an improvement.

The object of my invention is to provide a telephone-station apparatus with a secrecy-switch which may be set for communication over a line in either direction from the station, and may be left as long as desired in either of its two positions for communication without interrupting communication between stations between which may be located a station with its switch so adjusted or left. By this arrangement I prevent communication over the main line from being interrupted by the forgetfulness of a subscriber to return his switch to a normal position after finishing communication, and I also enable a subscriber to leave his switch in that position in which he most frequently uses it, thus obviating the necessity of frequent manipulation of the switch by subscribers who are in communication very often in one direction from their stations—as, for instance, from an express-office to a railway-depot.

In all secrecy-switches that I am aware of, constructed prior to my invention, the switch cuts the main line in such a manner that a manipulation or changing of the switch is necessary, first, to place the station in condition for secret communication with another, and,

second, to restore the continuity of the main line after the communication is finished. By my invention I greatly lessen the manipulation of the switch necessary by a subscriber, this being quite an item in those cases where the direction of communication lies on a particular side of a station.

In the accompanying drawings, Figure 1 illustrates a telephone-station apparatus provided with a secrecy-switch constructed according to my invention. Fig. 2 is a rear view of the switch-supporting board; and Fig. 3 is a section on line *xx*, Fig. 1.

The letter *A* designates the board or base which supports the call-bell and station-switches, the bell being indicated by the letter *B*.

Immediately below the bell a metallic switch-arm, *C*, is pivoted, at *c*, to the front of the base, and its free end may be swung into contact with either of two metallic plates, *D* or *D'*, also attached to the front of the base-board.

The lower portion of the base-board is recessed in the rear, and to the back of the board are secured metal strips *E* *E'*, which have their upper ends connected respectively with the plates *D* and *D'* by metallic wires or pins passing through the board, these pins being preferably screw-threaded and permanently connected to the plates *D*, as shown in Fig. 3, their rear ends passing through and engaging with the strips *E* *E'* and held in position by small nuts *d* *d*. The lower ends of the strips *E* and *E'* extend below the upper wall of the recess in the board and are bent, as shown at *e*, to extend into said recess.

To the side walls of the recess respectively are secured metallic plates, from the upper ends of which metallic springs *F* and *F'* extend toward each other under the bent portions *e* of the strips *E* and *E'*, the end of the spring *F'* overlapping the end of the spring *F*. The tension of these springs is such that they normally bear upward against the parts *e* of the strips *E* *E'*, and when in this position the ends of said springs will be out of contact with each other.

Immediately below the end of the spring *F'* there is secured to the board a vertical guide-

tube, G, in which plays a rod, H, the lower end of which is provided with a hook, h, and the upper end of which extends through a slot in the spring F' and is bent laterally to catch over the upper side of said spring. The hook h is to support the receiving-telephone T when said telephone is not in use, and when the hook is so weighted the rod H will be drawn downward, depressing the spring F', taking it out 10 of contact with the bent portion e of the strip E', and into contact with the spring F, forcing said spring downward and out of contact with the bent portion e of the strip E, as shown in dotted lines, Fig. 1, the springs being shown 15 as separated and in contact respectively with the strips E and E' in Fig. 2.

The main line entering the station is connected to a binding-post, l, which is connected by a wire, w, with the coils of the bell, from 20 which a wire, w', leads to the spring F', and a wire, w², leads from spring F to another binding-post, l', to which the other station-terminal of the main line is connected.

The pivoted end of the switch C is connected 25 by a wire, y, with a small binding-post, Y, to which is connected one of the wires of the receiving-telephone cord, the other wire of said cord being connected to a similar binding-post, Y', from which a wire, z, may lead to the ground 30 and include a transmitter in the ordinary way, if desired.

When the receiver T is on its hook, and the springs F and F' are in contact with each other and out of contact with the strips E and 35 E', the main-line circuit is completed as follows, in the direction indicated by the arrows No. 1—namely: from the binding-post l over the wire w, the bell-coils, wire w', springs F' and F, wire w², binding-post l', and is thus 40 complete through the station. Should, however, the receiving-telephone be removed from its hook and the springs F and F' become separated, as shown in Fig. 2, the main circuit will be broken at the station. It will thus 45 be seen that the springs F and F' form a gravity-switch by which the main line is joined to the strips E and E', and it is by the use of this gravity-switch, in conjunction with the switch C, that I give the latter the peculiar 50 characteristic of being capable of being left in either of its connecting positions without detriment to the continuity of the main-line circuit.

Should the subscriber desire to communicate with a station to the left, he moves the switch C into contact with the metallic plate D, takes his telephone off its hook, permitting the springs F and F' to rise and separate, the spring F coming in contact with the bent portion e of the strip E. The circuit is then completed from the main line in the direction indicated by the arrows No. 2 from the binding-

post l over wire w², spring F, strip E, plate D, switch C, wire y, to post Y, thence through the receiver back to post Y', and thence to the ground through a transmitter or not, as the case may be. When the communication is finished the subscriber simply hangs his receiver on its hook, thus closing the gravity-switch and restoring the main-line circuit; but he need 70 not take the trouble to remove the switch C from the plate D, as its remaining in contact with said plate will in no wise interfere with the main-line circuit, and may, besides, save him the trouble of placing the switch in contact with the said plate for his next communication. 75

If communication were desired to be had to the right of the station instead of the left, the subscriber would simply swing the switch C 80 into contact with the plate D, when the circuit would be formed from the post l, wire w, through the bell-magnet coils over wire w', spring F', strip E', plate D', switch C, wire y to the receiver and thence to the ground, as 85 before, the communication in both cases being secret, as the main circuit would run to ground at communicating stations, and any attempt of intermediate stations to interpose their telephones would result in grounding the main 90 circuit at such a station, and the original communicating subscribers would soon discover that they were no longer in communication.

Having now described my invention and explained the operation thereof, what I claim is— 95

1. In a telephone-station apparatus, the combination, with the main line and a telephone branch ground-line, of a secrecy-switch and a separate telephone branch switch, the latter being capable of closing and breaking the 100 main-line circuit independently of the former, but both co-operating to ground the main circuit through the telephone branch line, substantially as described.

2. The secrecy-switch, consisting of a pivoted metallic switch-lever and two metallic contacts, in combination with a wire leading from said lever to a telephone branch circuit, and a separate switch arranged to break the 105 main-line circuit and connect the two parts thereof with the contact-plates of the secrecy-switch, substantially as described.

3. The combination of the metallic switch-lever C, the contact-plates D and D', the springs F and F', telephone-supporting rod H, suitable projections from the said contact-plates into the paths of said springs, and the conducting-wires, substantially as described. 110

In testimony whereof I affix my signature in presence of two witnesses.

GEORGE W. COY.
